UNITED STATES PATENT OFFICE.

GEORGE M. PETTENGILL, OF HAVERHILL, MASSACHUSETTS, ASSIGNOR TO HAVERHILL SHOE MACHINERY COMPANY, A CORPORATION OF MAINE.

TOP-LIFT-CEMENTING MEANS FOR HEEL-NAILING MACHINES.

1,156,850.

Specification of Letters Patent. Patented Oct. 12, 1915.

Application filed November 18, 1910, Serial No. 592,978. Renewed January 8, 1914. Serial No. 811,097.

To all whom it may concern:

Be it known that I, GEORGE M. PETTENGILL, residing at Haverhill, in the county of Essex and State of Massachusetts, have invented an Improvement in Top-Lift-Cementing Means for Heel-Nailing Machines, of which the following is a specification.

This invention relates to certain improvements in heel nailing machines which are adapted to cement the top-lift automatically while held in the top-lift holder of the machine, and more particularly, it relates to means for performing this function which are especially adapted to be applied to a heel nailing machine of the vertically reciprocating cross-head and turret type, such as is shown in my pending application Serial No. 526,561.

The object of my invention is to provide a simple device of the above described character which will be effective in operation, and will be inexpensive to manufacture and unlikely to get out of order.

In the drawing, Figure 1 is a front elevation of the head portion of a heel-nailing machine provided with my invention, and showing the parts in one position. Fig. 2 is a detail view showing the parts in a different position. Figs. 3, 4 and 5 are enlarged detail views of the cement-applying device. Fig. 6 is a detail view of the top-lift holder.

In the drawing *a* indicates the main frame in which the carrier, or cross-head *b* is mounted to reciprocate vertically, said cross-head having a turret *c* rotatably mounted thereon, and said turret being provided with a driver arm *d* and a spanker and top-lift holder arm *e*.

The arm *e* has a top-lift holder mounted at its end which comprises a pair of adjustable jaws *f*, having converging edges for engaging the back edge of the top-lift, and a spring-actuated clamping bar *g* for engaging the breast edge. Instead of having the spanker arm *e* arranged either at 180° or 90° from the driver arm *d*, as has been customary, I arrange the same at an oblique angle thereto, so that the angle included between said arms *d* and *e* is approximately 45°, so that when the top-lift *x* is in position on the spanker plate, while the turret is in driving position, the lift will be held in an oblique position with relation to the vertical with its flesh or inner side facing downward,

The locking bolt *g* acts to hold the turret in either of its two positions.

As a matter of convenience, a top-lift tray *h* is secured to the inner side of the frame *a* beneath the cross-head, and said tray is provided at its front side with a depending lug *h'*, to which a horizontally disposed arm *i* is pivotally connected, said arm having a standard *j* adjustably mounted in the end thereof, at right angles thereto. A cement holder or receptacle *k* is mounted on the upper end of said standard *j* and a felt covered roll *m* is rotatably mounted in the sides thereof, so that the lower portion of the roll will be rotated in the cement contained by the receptacle, and the upper portion will project above the sides of the receptacle. The shaft of said roll is provided with a series of ratchet-teeth *q*, and a spring pawl *p* is mounted on the holder *k* in position to engage said teeth and prevent rotation of said roll to the right while permitting free rotation to the left. A bolt *n* is connected to the tray and passes through the arm *i*, and a spring *o* is inclosed between a head on the lower end of said bolt and the under side of the arm *i*, said spring acting to hold said arm *i* in an approximately horizontal position.

A stop screw *s* is mounted on the clamping bar *g* at the lift-engaging side thereof, and extends parallel thereto in position to engage the lower side edge of a top-lift held in the holder, when the holder is in its initial position shown in Figs. 1 and 2, for the purpose to be described.

The operation of the above described device is as follows:—A top-lift *x*, having been placed in the top-lift holder, as shown in Fig. 6, while the turret is locked in nailing position, in which the top-lift holder is held in its initial position, and the screw *s* having been adjusted so that its end bears against the lowermost edge of the lift, when the cross-head descends to perform the nail-driving operation, the top-lift will be carried vertically downward in the oblique position in which it is held, and, during the latter portion of this movement, into engagement with the roll *m*, the surface of which will be covered with cement. The roll will be engaged by the top-lift at a point on the latter a short distance from its lowermost edge, and, on further downward movement of the cross-head, the cementing-roll will be

rolled across the surface of the lift, and when the cross-head reaches the limit of its downward stroke the lift will have moved in contact with the roll to a point within a short distance of the uppermost edge of the lift. At the same time the roll *m*, together with its receptacle *k*, will be pushed downward to a slight extent, this movement being permitted by the downward swinging of the 10 arm *i* against the action of its supporting springs, as shown in Fig. 2. It will be apparent that any other suitable means which will permit the cement-applying surface to yield sufficiently to permit the vertical, 15 downward movement of the obliquely held top-lift, while in engagement therewith, will serve the purpose, the construction shown being preferable, I believe, to any of which I am, at present, aware. On the return, or 20 upward movement of the cross-head, the cementing roll would be rotated in the opposite direction, but for the pawl *p*, which engages the ratchet *q* thereon, and prevents such rearward rotation, so that, as the top-lift is carried upward, the roll will drag on the surface of the lift until the lift is carried out of engagement therewith, the spring *o* lifting the arm *i* to its normal position. As there is some frictional engagement be- 25 30 35 40 45 50 55

tween the top-lift and the cementing-roll on this return movement, the roll has a tendency to pull the top-lift out of the holder, and to prevent such occurrence the stop-screw *s* is provided, which bears against the lower edge of the lift and prevents such an occurrence. It will be observed that the cementing-roll is thus caused to rotate forwardly on each reciprocation of the cross-head and thus to rotate in the cement contained in the receptacle *k*, so that a freshly coated surface of cement is presented to the top-lift on each cementing operation.

While I prefer to have the spanker arm *e* held at approximately 45° from the driver arm *d*, so that the swing of the turret will be as short as possible, and yet the spanker arm will not be so close to the operator as to interfere with the heel attaching operation, it will be obvious, that, so far as the cementing operation *per se* is concerned, it may be performed more or less satisfactorily with the spanker arm held at various other angles between a horizontal and a vertical position, the limits of variation from the middle position shown being defined by practical considerations.

I claim:—

1. In a heeling machine, a vertically reciprocating top-lift holder, adapted to support a top lift in a position oblique to the vertical and facing downward, and a cementing device arranged directly in the path of movement of the lift as it is carried downward in said position by the holder.
2. In a heeling machine, a vertically re-

ciprocating carrier having a top-lift holder thereon adapted to support a lift in a position oblique to the vertical and facing downward, during a downward movement of said carrier, and a cementing device arranged directly beneath said holder in position to be engaged by a lift held thereby on downward movement of the carrier. 70

3. In a heeling machine, a vertically reciprocating cross-head and a turret mounted thereon having an arm provided with a top-lift holder at its end arranged to hold the lift at right angles to said arm, means for locking the turret in a position in which said arm extends obliquely downward, and a cement holder mounted directly beneath said holder in position to be engaged by the lift held thereby on downward movement of the cross-head. 75 80

4. In a heeling machine, a vertically reciprocating carrier having a top-lift holder movably mounted thereon, and means for locking said holder in position to hold a lift with one side oblique to the vertical and facing downward during a downward movement of the carrier, and means for yieldingly supporting said cementing device beneath said holder in position to engage a lower portion of the side of a lift held thereby, and to be held in engagement therewith during a portion of said downward movement. 85 90 95

5. In a heeling machine, a vertically reciprocating carrier having a top-lift holder movably mounted thereon, and means for locking said holder in position to hold a lift with one side oblique to the vertical and facing downward during a downward movement of the carrier, a cementing roll, and means for supporting said roll to rotate about a horizontally disposed axis, beneath a lift held by said holder, in position to be engaged by the lift and to roll across a portion thereof during said downward movement. 100 105 110

6. In a heeling machine, a vertically reciprocating carrier having a top-lift holder movably mounted thereon, and means for locking said holder in position to hold a lift with one side oblique to the vertical and facing downward during a downward movement of the carrier, a cementing roll, and means for yieldingly supporting said roll to rotate about a horizontally disposed axis, beneath a lift held by said holder, in position to be engaged by a lower portion of the side of the lift and to roll thereover to an upper portion thereof as it is pushed out of the path of the lift during said downward movement. 115 120 125

7. In a heeling machine, a vertically reciprocating carrier having a top-lift holder movably mounted thereon, and means for locking said holder in position to hold a lift with one side oblique to the vertical and 130

- facing downward, during a downward movement of the carrier, a cementing roll, means for yieldingly supporting said roll to rotate about a horizontally disposed axis, 5 beneath a lift held by said holder, in position to be engaged by a lower portion of the side of the lift and to roll thereover to an upper portion thereof as it is pushed out of the path of the lift during said downward movement, means for preventing opposite rotation of the roll on the upward movement of the carrier, and means for supplying cement to the surface of the roll. 10
8. In a heelng machine, a vertically reciprocating carrier having a top-lift holder movably mounted thereon, and means for locking said holder in position to hold a lift with one side oblique to the vertical and facing downward during a downward movement of the carrier, a cement receptacle, and a roll mounted to rotate therein about a horizontally disposed axis, and beneath a lift held by said holder, in position to be engaged by the lift during said downward movement and to cause said roll to rotate. 15
9. In a heelng machine, a vertically reciprocating carrier having a top-lift holder movably mounted thereon and means for locking said holder in position to hold a lift with one side facing downward during a downward movement of the carrier, a spring-supported arm, a cement receptacle mounted on said arm, and a cementing roll mounted to rotate therein beneath a lift held 20 by said holder in position to be engaged by the lift during said downward movement.
10. In a heelng machine, a vertically reciprocating carrier having a top-lift holder movably mounted thereon and means for locking said holder in position to hold a lift with one side facing downward during a downward movement of the carrier, a spring-supported arm, a cement receptacle mounted for vertical adjustment on said 25 arm, and a cementing roll mounted to rotate therein beneath a lift held by said holder in position to be engaged by the lift during said downward movement.
11. In a heelng machine, a vertically reciprocating carrier having a top-lift holder movably mounted thereon, and means for locking said holder in position to hold a lift with one side oblique to the vertical and facing downward during a downward movement of the carrier, a stop on said holder for engaging the lowermost edge of a top-lift held thereby, a cementing roll, means for yieldingly supporting said roll to rotate about a horizontally disposed axis beneath a lift held by said holder, in position to be engaged by a lower portion of the side of the lift and to roll thereover to an upper portion thereof as it is pushed out of the path of the lift during said downward movement, means for preventing opposite rotation 30 of the roll on the upward movement of the carrier, and means for supplying cement to the surface of the roll. 70
12. In a heel-attaching machine, a head movable successively to perform the heel-attaching and top-lift spanking operation, a top-lift holder on said head, movable to and from a top-lift-spanking position, a cementing device, and means to lock said holder in a position at one side of its said 75 spanking position to carry a lift held thereby into engagement with said cementing device during the heel attaching movement of said head. 75
13. In a heel attaching machine, a reciprocating head having a turret thereon arranged to swing within a right-angle between heel-attaching and top-lift spanking positions, a top-lift holder on said turret arranged to hold the lift to face outwardly, a cementing device, and means to lock said turret to hold said top-lift holder in position to carry the lift into engagement with said cementing device during the heel attaching movement of said head. 80
14. In a heelng machine, a reciprocating head having a turret thereon arranged to swing within a right-angle between a heel-attaching, and a top-lift-spanking position, and means to lock the turret in each of said 85 positions, a top-lift holder on said turret arranged to hold the lift to face outwardly, and a cementing device arranged in the path of the face of a lift in said holder when the turret is held in heel-attaching position and is moved to perform the heel-attaching operation, whereby the heel-attaching and top-lift cementing operation are performed by the same movement of the head. 90
15. In a heelng machine, a vertically reciprocating head having a turret thereon arranged to swing between a heel-attaching and a top-lift-spanking position, and means to lock the turret in each of said positions, a top-lift holder on said turret arranged to hold the lift to face outwardly in a position which, when the turret is in heel-attaching position, is within a right angle of its spanking position, and a cementing device arranged to be engaged by the face of a top-lift in said holder when the turret is held in said heel-attaching position, and said head is moved to perform the heel-attaching operation, whereby cement is applied to said face during said operation. 95
16. In a heelng machine, a vertically reciprocating head having a turret thereon arranged to swing between a heel-attaching and a top-lift-spanking position, and means to lock the turret in each of said positions, a top-lift holder on said turret arranged to hold the lift to face outwardly in a position which, when the turret is in heel-attaching position, is within a right angle of its spanking position, and a cementing roll 100
- 110
- 115
- 120
- 125
- 130

mounted to rotate in the direction of movement of said head and arranged to be engaged by the face of a lift held by said holder when the turret is held in heel-attaching position and said head is moved to perform the heel-attaching operation to cause said roll to be rotated by the lift while engaged thereby.

In testimony whereof, I have signed my name to this specification, in the presence of 13 two subscribing witnesses.

GEORGE M. PETTENGILL.
